UNITED STATES PATENT OFFICE.

HARRY J. MYERS, OF ROCHESTER, NEW YORK.

VALVE AND VALVE-OPERATING DEVICE FOR AIR-PUMPS.

SPECIFICATION forming part of Letters Patent No. 651,081, dated June 5, 1900.

Application filed June 30, 1899. Serial No. 722,454. (No model.)

To all whom it may concern:

Be it known that I, HARRY J. MYERS, a resident of Rochester, in the county of Monroe and State of New York, have invented certain new and useful Improvements in Valves and Valve-Operating Devices; and I do hereby declare the following to be a full, clear, and exact description of the invention, such as will enable others skilled in the art to which it pertains to make and use the same.

The invention relates to valves, adapted to be automatically opened and closed, of the general nature of those used to admit and cut off fluid-pressure for operating a pump—as, for example, for moving the bell of an air-pump adapted for supplying air to a carbureter or carbureted gas or other fluid to a holder or to a point of consumption.

The object of the invention is to improve valves of the general character described; and the invention consists in the construction hereinafter described and pointed out.

In the accompanying drawings, Figure 1 is a section of the device applied to an air-pump. Fig. 2 is an enlarged section of the improved valve. Fig. 3 is a similar section of a modification of the valve.

Numeral 1 denotes a valve-casing, 2 a piston or spindle valve, and 3 a valve-operating lever having a fulcrum in the valve-case bracket 4, provided with lever-stops 5.

6 and 7 denote, respectively, an inlet and outlet of the valve-casing, and 8 a vent or casing-discharge.

The valve 2 has a lengthwise-disposed port 9, closed at its upper end and open below and communicating with a transverse port 10, extending through one side of the valve to said port 9, as shown.

11 and 12 denote circumferential ports formed in the valve, and 12^x is a transverse port by which circumferential port 12 and longitudinal port 9 communicate. A fluid under pressure, such as water from a main, enters inlet 6 and when the valve is suitably situated passes about said valve through port 11 and out at 7 to a pump or the like to actuate the same. This water admission and pressure can be cut off by lowering the valve so that port 11 does not register with the inlet 6. If the valve be lowered so that port 10 registers with the outlet 7, the water or other

fluid which has done its work can be discharged through said port 10 and port 9. If the fluid is not to be discharged, port 10 can be dispensed with and the lower end of port 9 closed. The pressure of the fluid admitted by the valve may be utilized in any known or desired manner, as by a rod, piston, bar, or the like part 13, to be suitably connected to a pump or other mechanism—as, for example, to a piston or plunger 23', working in a cylinder 23, the piston being fixed to the bell 24 of an air-pump having in general the well-known form of a gasometer.

14 denotes a bar fixed to the bell and provided with tripping-fingers 14', coöoperating with valve-moving mechanism, which comprises a rod 15, pivoted to the valve-lever at 16 and suitably guided, as at 17. 18 denotes pins fixed on said rod in the path of an arm 19' of a weighted bell-crank lever 19, having a fulcrum at 19".

20 denotes a weight adjustably connected to lever 19.

As shown in the present instance, the bar 13 forces upward the bell 24 to draw in air at 25, the bell being raised by means of piston 23', forced up by the fluid admitted through the valve beneath said piston. The piston-rod and the bell to which it is secured are lifted until the lower finger 14' turns the bell-crank lever 19 and carries its weight beyond the center of its arc of movement, whereby said weight falls by gravity and lifts the valve 2 to close circumferential port 11 by moving it out of registry with the valve-casing inlet and outlet. If desired, the construction may be as illustrated and so that the escape-ports 10 may register with outlet 7 to permit wastage of the motor fluid that has been used. The pump-bell being thus raised is filled with air through inlet 25, provided with a check-valve and in usual manner. When suitably filled with air, the bell is returned by gravity, its weight being augmented by supplementary weights, if required. The descent of the bell forces its contained air (or other fluid) to any desired point through a suitable valve conduit or conduits 26. The admission-valve 2 remains closed until the descent of the bell carries the upper finger 14' of rod 13 against the arm 19' of lever 19 and lifts the weight, carrying it over until it drops and turns the

lever on its pivot to cause its arm 19' to strike the lower pin 18 with the effect to reopen the valve and admit the motor fluid to repeat the operation.

5 In case the improvement is applied to a construction not requiring the return of waste water through the valve a single transverse spindle-port 10^x (see Fig. 3) will be used, and of course such single transverse port will not communicate with a waste-port, such as 9. The upper circumferential port 12 may have such communication or not, as desired under particular conditions of use. Said port 12 receives leakage from below and maintains lubrication of the spindle. It also obviates leakage at the upper part of the spindle-cylinder. In the form preferred a surplus of water leakage into port 12 is discharged through port 9. The port 12 not only arrests 15 water forced upward about the spindle and prevents leakage at the top of the valve-casing, but it arrests sediment that would otherwise wear the spindle or stem of the valve above said port. The construction enables 20 packing or a stuffing-box to be dispensed with, and the valve works freely in all ordinary extremes of temperature without sticking and without injurious wear and leakage.

It is not essential that the valve-lever be 25 supported on a bracket fixed to the valve-casing nor that the stops which limit the path of the lever be a part of the bracket-arm. Neither is it essential that the guide for rod 15 and the weight-rest 21 be integral with or 30 fixed to the bracket, such as 24, which supports the bell-crank lever, though the constructions illustrated are suitable and in many cases preferred. These and other details may be varied, provided the substantial 35 principles of operation and construction are preserved.

Having thus described my invention, I claim—

1. A valve-casing having an inlet and an outlet, an endwise-movable valve within the casing and provided with an interior port, said valve being formed with a circumferential port and with a wastage-port, the latter being in communication with the interior port of 45 the valve, whereby fluid may be caused to flow around the valve and out the outlet from the casing or back through the outlet to the interior port of the valve according to the situation of the valve.

50 2. The valve-casing having an inlet and an outlet, an endwise-movable valve in the casing leaving an interior port closed at the upper end, a circumferential port adapted when the valve is properly situated to establish communication between the inlet and outlet of 55 the casing, and a wastage-port adapted to establish communication between the outlet of the casing and the interior port of the valve, as and for the purpose stated.

65 3. A valve-casing having an inlet and an out-

let, a valve formed with an interior port, a circumferential port formed in the valve to permit the fluid to flow around the valve and out the outlet of the casing, a wastage-port forming a communication between the casing-outlet and the interior port of the valve, and a second circumferential port formed in the valve and communicating with the interior port to carry off overflow in the operation of the valve.

4. The valve-casing having an inlet and an oppositely-situated outlet, the endwise-movable valve having the circumferential admission-port whereby said inlet and outlet communicate, and a wastage-groove communicating by a port with the port within the valve and leading to the discharge from the casing.

5. A valve having an interior port open at the lower end and closed at the upper end, a main circumferential port formed in the valve, a wastage-port leading from the interior port, and an overflow-channel circumferentially formed in the valve and having a port in communication with the interior valve-port and a casing in which said valve is adapted for endwise movement.

6. The combination of a gasometer-float adapted for vertical movement by fluid-pressure, a valve-casing having an inlet and an oppositely-situated outlet, an endwise-movable valve having a circumferential admission-port whereby said inlet and outlet communicate and a wastage-groove communicating by a port with the port within the valve and leading to the discharge from the casing, and means intermediate the float and valve to automatically control the latter by the operation of the former.

7. The combination of a gasometer-float adapted for vertical movement by fluid-pressure, a valve-casing having an inlet and an oppositely-situated outlet, an endwise-movable valve having a circumferential admission-port whereby said inlet and outlet communicate and a wastage-groove communicating by a port with the port within the valve and leading to the discharge from the casing, and means intermediate the float and valve to automatically control the latter by the operation of the former, said means comprising a rod fixed to the float and provided with vertically-adjustable fingers, a weighted bell-crank lever adapted to be rocked by said fingers, and a rod operatively connected to the valve, said rod being provided with pins in the path of the bell-crank lever, substantially as described.

In testimony whereof I have signed this specification in the presence of two subscribing witnesses.
